H. G. Burns ATTORNEY

UNITED STATES PATENT OFFICE.

JOSEPH EDWARD SMITH, OF FORT WAYNE, INDIANA, ASSIGNOR OF ONE-THIRD TO
GEORGE C. DIERSTEIN, OF FORT WAYNE, INDIANA.

MILK HEATER AND CLARIFIER.

Application filed June 13, 1924. Serial No. 719,757.

This invention relates to improvements in milk heaters and clarifiers and the object thereof is to provide an apparatus for subjecting milk in large quantity to the action of heat and centrifugal force, and to construct the apparatus so that its several parts that have contact with the milk may be readily dismembered for cleansing purposes and reassembled.

10 These objects are accomplished by the construction illustrated in the accompanying drawing which is a vertical elevation showing a construction embodying the invention, there being parts broken away and other portions in section.

The characters appearing in the description refer to parts shown in the drawings and designated thereon by corresponding characters.

20 The invention comprises a revolving head 1 mounted fixedly upon a vertically disposed shaft 2 which is connected with a gearing 3 located in the base 4 of the machine. The upper part of the shaft 2 extends loosely through a bushing 5 in the upper end of which is a ball bearing 6 for the shaft, and the lower end of which is conical and fits in a block 7 the bore of which is tapered corresponding to the conical bushing. The block 7 is vertically movable in a stationary box 8, and an extension spring 9 in the box bears upwardly against the block so that the block tends to center the conical bushing within its bore. When 35 the head is rotated at high velocity it may assume its natural axis of rotation which is permitted as the block 7 yields to the pressure of the conical bushing and accommodates the lateral movements of the bushing that are occasioned by the swing of the revolving head to its natural axial center.

Upon the head 1 is removably mounted a cylindrical vessel 10, the wall of which tapers inwardly from the bottom to the top, and upon the top of the vessel is a removable head 11 to the underside of which is secured a drum 12 which has a head 13 at its lower end with a perforated flange 14 that extends into a groove in the base 15 of the vessel 10, there being a space 16 between the head 13 of the drum and said base. Vertically disposed tubes 17 and 18 in concentric annular groups extend through the

drum, the ends of each tube extending through the heads 11 and 13. 55

Upon the top of the head 11 is a cylindrical shell 19 upon the upper end of which is a removable cover 20, and within said shell is an annular perforated baffle 21, the lower edge of which extends into the top of the head 11 between the two groups of tubes. Also upon the top of the head 11 and surrounding the shell 19 is a jet ring 22 having discharge openings 23 therein that have communication with the chamber 24 within the vessel 10 and external of the drum. A splash ring 25 is positioned at the junction of the head 11 and the jet ring. The head 11 has discharge openings 26 that extend from the chamber 27 within the drum 12 to the external perimeter of the head 11. 70

A tubular casing 28 extends through the head 11 in line with the axial center thereof and has a tapered lower end that projects into a perforated box 29 that is fixed 75 on the lower head 13 of the drum, the casing being positioned rigidly. A nozzle 30 connected with a steam pipe 31, extends downwardly through the casing 28 to a point adjacent its lower end and is sustained centrally within the casing through its connection with the steam pipe. 80

Upon the machine frame 4 is a bracket 32 which supports an annular catch pan 33 that surrounds the vessel 10 with its inner 85 lip 34 located below the discharge openings 26 in the head 11. Upon said pan is supported a second annular catch pan 35 that surrounds the jet ring with its inner lip 36 located below the discharge openings 23 90 therein and above the splash ring 25 that projects between the inner lips of the catch pans. Upon the uppermost catch pan is mounted a removable cover 37 which affords support for a funnel 38 which is located with its tubular discharge end 39 extending through the cover 20, there being a central tube 40 extending through the funnel and surrounding the upper part of the casing 28 without contact therewith. 95

In utilizing the invention the gearing is driven by a belt connection 41 with a suitable source of power such as a motor 42 so that the head is rotated at high velocity. Steam is admitted through the nozzle 30 and 105 fills the chamber 27 within the drum caus-

ing the tubes therein to become heated, and water that results from the condensation of the steam is thrown against the inner wall of the drum 12 by centrifugal force and is 5 expelled through the discharge openings 26 into the catch pan 33. The milk to be treated is supplied to the funnel through which it is introduced into the shell 19. A portion of the milk passes directly through 10 the series of tubes 17 into the lower end of the vessel 10, while another portion of the milk passes through the perforated baffle 21 and flows through the series of tubes 18. The milk flowing through all of the tubes 15 is heated through the action of the steam in the drum and passes from the space at the bottom of the drum through the perforated flange into the chamber 24 within the vessel and surrounding the drum. Owing to centrifugal force the milk is thrown against 20 the inner face of the vessel and flows up to and out through the discharge openings 23 into the catch pan 35. As the lower portion of the vessel 10 is of greater diameter than 25 the top, the heavy impurities and foreign matter contained in the milk are detained while the heated milk thus relieved of such matter passes on into the catch pan. The accumulated substances form a dense mat 30 against the vertically inclined wall of the vessel which mat is removed after separating the drum from the vessel to permit the interior of the apparatus to be cleansed.

What I claim is:—

35 1. In apparatus of the class described, a rotating member comprising a tapering cylindrical vessel, a drum extending into the vessel in axial alinement therewith and having two concentric series of vertical tubes 40 extending therethrough; a shell having a cover at its top and encompassing the adjacent ends of said tubes; an annular perforated baffle in the shell with its lower end positioned between the two series of tubes; 45 a jet ring having discharge openings there-

in communicating with the chamber of the vessel, there being another set of discharge openings for the chamber of said drum extending through the upper head thereof in a plane beneath the discharge openings of 50 said ring; stationary means for receiving separately the discharge from the vessel and the drum through the corresponding discharge openings therefor; means for supplying steam to the drum chamber; means for 55 supplying milk through the cover of the shell into the baffle; and a mechanism for actuating the revolving member.

2. In apparatus of the class described, a 60 rotating member including a tapering cylindrical vessel and a drum axially alined therein, there being separate discharge openings for the vessel and the drum the outlet ends of the discharge openings for the vessel being located in a horizontal plane above 65 those for the drum; vertical tubes extending through the drum; means for supplying milk to said vessel through said tubes; means for supplying steam to the drum; stationary catch pans positioned respectively to 70 receive the discharge from the vessel and drum separately through the corresponding discharge openings therefor; and mechanism to actuate the revolving member.

3. In apparatus of the class described, a 75 rotating vessel; a drum axially alined therein, there being separate discharge openings for the vessel and the drum located in different horizontal planes; two concentric series of vertical tubes extending through 80 the drum; an annular perforated baffle on the upper head of the drum separating the two series of tubes at their receiving ends; a shell encompassing the upper ends of the tubes and the baffle; heating means for the 85 drum; a milk supply means discharging into the baffle; and means for receiving the discharge from the vessel and drum separately.

In testimony whereof I affix my signature.

JOSEPH EDWARD SMITH.
